DESIGN FOR BRAID

Max Singer, Brooklyn, N. Y.

Application November 12, 1942, Serial No. 108,754

Term of patent 3½ years

To all whom it may concern:

Be it known that I, Max Singer, a citizen of the United States and a resident of Brooklyn, in the county of Kings and State of New York, have invented a new, original, and ornamental Design for Braid, of which the following is a specification, reference being had to the accompanying drawing, forming part thereof, and in which the figure is a plan view of a length of braid, showing my new design.

I claim:

The ornamental design for braid, substantially as shown.

MAX SINGER.
